UNITED STATES PATENT OFFICE

2,419,771

HIGH REACTANCE TRANSFORMER

Edwin G. Goddard, Lombard, Ill., assignor to
 Jefferson Electric Company, Bellwood, Ill., a
 corporation of Illinois

Application August 15, 1942, Serial No. 454,948

3 Claims. (Cl. 171—119)

1

My invention relates to high reactance transformers and more particularly to a transformer of this type for loads having negative resistance characteristics and which has a high power factor over an extended operating range.

Heretofore high reactance transformers have been designed so as to have relatively constant output characteristics so as to supply power to loads having negative resistance characteristics such as is found in luminous tube lighting. By using an auxiliary winding and a capacitor it is possible to design a transformer of this type so that for a particular load the transformer will operate with a relatively high power factor. In commercial practice, however, the load usually differs from the particular load assumed in such design, and hence it is apparent that such transformers do not always operate with the desired power factor. Some of the factors affecting the power factor of such high reactance transformers are brought about by the variations in the tube lengths of the luminous signs, since obviously the length of every sign can not be held within a narrow limit, and in making such lighting installations there may also occur inequalities in the gas pressure contained within the luminous tubes. Furthermore it is not feasible to provide a specific transformer for each specific length of luminous tubing, and hence these transformers are used over an appreciable range of luminous tubing.

It furthermore is possible from a theoretical standpoint to improve the power factor of transformers over a considerable range, but this is not necessarily commercially feasible since it is necessary to consider the economics of manufacture and sale. Accordingly by means of the present invention it is intended to provide to a considerable degree the desired characteristics in a high reactance transformer which will operate over an extended range of loads at a greatly improved power factor as compared to transformers now readily available on the market. More particularly this is accomplished by providing a capacitive reactive effect which varies in response to different loads so as to tend to correct the power factor of the transformer, thereby extending the range over which the transformer may be operated at a relatively high power factor.

It is therefore an object of my invention to provide an improved transformer arrangement of a type having limited current output characteristics which may be assembled in a unit economical to manufacture and which will overcome the above mentioned disadvantages of the prior art.

Still another object of my invention is to pro-

vide an improved transformer arrangement of the type having limited current output characteristics which will provide relatively high power factor operation over an extended range.

5 Still another object of my invention is to provide a high reactance limited current output transformer which is provided with a capacitive reactance which varies in response to different load conditions.

10 A further object of my invention is to provide an improved transformer arrangement of the type having a limited current midpoint grounded secondary winding which will provide relatively high power factor over an extended load range.

15 A still further object of my invention is to provide a high reactance transformer arrangement which when connected to a power line having harmonics will reduce to a negligible degree the tendency thereof to reduce the power factor.

20 A still further object of my invention is to provide an improved transformer arrangement having a winding loosely coupled with respect to the primary winding and arranged to supply a reactive effect tending to correct the power factor of the transformer.

25 Other and further objects of my invention will become more readily apparent by reference to the following description taken in connection with the accompanying drawing wherein:

30 Figure 1 represents the physical arrangement of the magnetic core structure and the location of the windings thereon;

Fig. 2 shows the electrical equivalent of the structure arrangement shown in Fig. 1; and

35 Fig. 3 is a graphical representation illustrating the improved operational characteristics obtained by the present invention.

Referring more particularly to Figs. 1 and 2, it will be seen that there is provided a magnetic core structure 5 supporting a plurality of coils 6, 7, 8, and 9 thereon, and further that the magnetic core structure 5 has magnetic shunt portions 11 and 12 positioned between certain of these coils. The transformer is provided with an input winding 6 which is adapted to be connected to a suitable source of alternating current voltage E_p . An auxiliary winding 7 is supported on the core 5 adjacent to the primary winding 6 so as to be loosely coupled with respect thereto.

40 The end of the winding 7 adjacent the coil 6 is connected to the adjacent end thereof, the other end of the auxiliary winding 7 is connected to a capacitor 13, which in turn is connected to the end of the input winding 6. The input winding 6 and auxiliary winding 7 are separated from the coil

portions 8 and 9 by portions of the magnetic core so as to provide a high leakage reactance characteristic for the transformer. The windings 8 and 9 each have the inner terminals grounded and the outer terminals are connected to supply the load E_L having negative resistance characteristics as is the case where the transformer is used to supply luminous tubes.

From the physical arrangement of the output windings 8 and 9 illustrated in Fig. 1, it will be seen that they are not symmetrical with respect to the primary winding 6, and hence it is to be understood that one of the windings has a few additional turns so as to compensate for the physical arrangement, thus to provide an electrically balanced relation between the primary and secondary windings which may be called a midpoint grounded secondary transformer arrangement. By providing a midpoint grounded secondary winding, it is to be understood that an electrical balance has been provided for.

Since the transformer arrangement shown is generally enclosed in a suitable case formed of metal, it will be appreciated that the case is physically close to the windings 6 to 9. Thus the case assists in providing leakage reactance paths in addition to the magnetic shunts 11 and 12. Furthermore, a leakage path is provided between the primary winding 6 and the auxiliary winding 7 so that where a case is used this leakage path is taken into consideration in determining the design of the auxiliary winding and the size of the capacitor 13. Thus it will be seen that a loose coupling is provided between the primary winding 6 and the auxiliary winding 7, and also that a high reactance is obtained by virtue of the paths 11 and 12 together with the influence of the case. Accordingly with different load conditions the high reactance provided by such an arrangement will operate to limit the current output of the secondary windings 8 and 9. Thus the transformer leakage reactance tends to compensate for a reduction in the load impedance which would tend to cause the output current to peak.

The loose coupling between the input winding 6 and the auxiliary winding 7 changes in accordance with the current value of the load E_L so that the capacitive reactance provided by the auxiliary winding and the capacitor is not a constant effective quantity but one which varies in accordance with the load. The curve 14 represents the power factor characteristics of a transformer arrangement which has been provided with a capacitive reactance designed for a particular load value. The curve 15 represents the power factor characteristics of the transformer arrangement heretofore illustrated and described. By comparison of these two curves it will readily be seen that a much wider load range of operation is obtainable for a particular power factor by the improvement shown than by former arrangements which are illustrated by the curve 14.

Due to the particular arrangement of the auxiliary winding and the capacitor, there is obtained a variation in the effective reactances of the elements so that there is a definite improvement with respect to the harmonics of the power line since the capacitive reactance is reduced at the higher harmonic frequencies thereby resulting in considerable improvement in operation.

My improved transformer arrangement of the high reactance type therefore is particularly suitable for use over an appreciable range of loads including those loads having negative resistance characteristics, although other types of loads may also be used. There is also considerable improvement of the reduction of harmonic influence of the power line.

While for the purposes of illustration a particular arrangement has been described, it is to be understood that variations may be made in the arrangement and in the circuit instrumentalities employed without departing from the spirit and scope of my invention as defined in the appended claims.

What I claim as new and desire to secure by Letters Patent of the United States is:

1. A high leakage reactance transformer comprising a magnetic core structure having thereon a primary winding adapted to be connected to a source of alternating current, an auxiliary winding mounted on said core structure directly adjacent one end of said primary winding, one end of said auxiliary winding being connected to the adjacent end of said primary winding, a capacitor connected between the other ends of said auxiliary winding and said primary winding, and a divided secondary winding arranged on said core structure so as to be balanced in voltage with respect to said primary winding, said core structure having high leakage reactance paths between said secondary winding and said first mentioned windings.

2. A high leakage reactance transformer comprising a magnetic core structure having thereon an input winding adapted to be connected to a source of alternating current, an output winding supported by said core structure and arranged to be in electrically balanced relation to said input winding, said core structure being provided with magnetic shunt means between said windings, an auxiliary winding mounted adjacent said input winding on the same leg of said core structure, and a capacitor connected across said auxiliary winding and said input winding.

3. A high reactance high power factor transformer arrangement comprising a primary winding, an auxiliary winding positioned directly adjacent thereto and being directly connected to said winding, a capacitor connected across both said windings, a midpoint grounded secondary winding, and a magnetic core structure for said windings, said core structure being provided with magnetic shunt portions positioned between said secondary winding and said other windings to provide high leakage reactance characteristics.
